UNITED STATES PATENT OFFICE

147,621

DESIGN FOR A BROOCH OR SIMILAR
ARTICLEPaul Marino, Pawtucket, R. I., and Ernest Steiner,
New York, N. Y.

Application May 10, 1946, Serial No. 129,554

Term of patent 3½ years

(Cl. D45—19)

To all whom it may concern:

Be it known that we, Paul Marino and Ernest Steiner, both citizens of the United States and residents respectively of Pawtucket, county of Providence, and State of Rhode Island, and New York city, county and State of New York, have invented a new, original, and ornamental Design for a Brooch or Similar Article, of which the following is a specification, reference being had to the accompanying drawings, forming part thereof and in which

Fig. 1 is a front elevational view of a brooch showing our new design, and

Fig. 2 is a side view thereof.

We claim:

The ornamental design for a brooch or similar article, substantially as shown.

PAUL MARINO.
ERNEST STEINER.
